UNITED STATES PATENT OFFICE.

OLE T. BELSVIG, OF MILAN, MINNESOTA.

LATCH.

No. 926,090

Specification of Letters Patent.

Patented June 29, 1909.

Application filed March 9, 1909. Serial No. 462,333.

To all whom it may concern:

Be it known that I, Ole T. Belsvig, citizen of the United States, residing at Milan, in the county of Chippewa and State of Minnesota, have invented new and useful Improvements in Latches, of which the following is a specification.

My present invention pertains to latches for doors, gates and the like; and it has for one of its objects to provide a simple, strong and easily applied latch of the spring type, and adapted to be used to advantage on sliding as well as swinging doors and gates of all kinds.

Another object of the invention is the provision in combination, of a door, a latch carried thereby, means for co-operating with the latch to fasten the door when the same is closed, and means for co-operating with the latch to hold the door when the same is swung to a fully opened position.

Other objects and advantageous features of the invention will be fully understood from the following description and claims when the same are read in connection with the drawings, accompanying and forming part of this specification, in which:

Figure 1 is an elevation showing my improvements arranged for use in combination with a swinging door; the door being in its closed position. Fig. 2 is an enlarged detail perspective view illustrative of the manner in which the door is held open by the co-operation of the latch and a keeper. Figs. 3 and 4 are detail transverse sections, taken through the latch in the planes indicated by the lines 3-3 and 4-4, respectively, of Fig. 5. Fig. 5 is a detail section taken through the latch and door. Fig. 6 is a detail perspective view showing the use of the latch in connection with a pad lock, as when it is desired to lock a door or gate. Fig. 7 is a detail perspective view of the latch bar that may be used when it is not desired to lock the door or gate. Fig. 8 is a similar view of the latch bar that is employed when the latch is applied to a sliding door or gate.

Referring by letter to the said drawings and more particularly to Figs. 1 to 6 thereof: A is the side of a barn or like place. B is a swinging door. C, Figs. 1 and 2, is a beveled keeper, fixed to the side of the barn or upon any other suitable fixed support and notched, as indicated by a. D is a beveled keeper arranged at the opposite side of the door, with reference to the beveled keeper

C, and notched, as indicated by b, and apertured at c. E is a wear plate suitably fixed to the face of the door and provided with a retaining strap d and F is a hole bored or otherwise formed transversely through the door and wear plate for the reception of the casing of my novel latch.

The latch casing is best shown in Fig. 5 and by reference to that figure the casing will be seen to be made up of an intermediate tubular section G, exteriorly threaded at its ends, an end tubular section H screwed on one end of the intermediate section, and an end tubular section I screwed on the opposite end of the intermediate section and having a slot e, Figs. 2 and 5. Intermediate the end section H of the casing and the adjacent side of the door I prefer to arrange a metallic ring J, the office of which is to prevent the end section H marring the door.

It will be manifest from the foregoing that in applying the latch casing, it is simply necessary to first place one of the end sections on the intermediate section and then insert the intermediate section in the bore F until it projects beyond the other side of the door. Then the other end section is screwed on the projecting end of the intermediate section until both end sections are firmly fixed against opposite sides of the door. From this it will be obvious that if desirable one of the end sections may be fixed to or formed integral with the intermediate section, without involving departure from the scope of my invention as claimed.

In the casing described is arranged a coiled spring K, one end of which is fixed to the casing at f, and through the said spring is extended the spindle L of a handle M which latter is disposed at one end of the casing. The spindle L is connected at g to the spring K and is turned through the medium of its handle M to put the spring under tension to the extent desired. This tightening of the spring is accomplished before the spindle, of angular form in cross-section, is moved endwise through the angular aperture h of the latch bar N, and subsequently a second handle P is turned on the threaded end i of the spindle and secured by a nut j.

As will be best seen by reference to Fig. 6, the latch bar N terminates in a vertically-disposed and apertured portion R which is

adapted, when the latch bar seats in the notch of the keeper D, to assume a position alongside the said keeper, this in order that the two may be secured together and the door locked in its closed position through the medium of a pad-lock S.

When it is not desired to lock the latch bar to the keeper D, a latch bar N' such as shown in Fig. 7 may be employed, and the 10 aperture c in the keeper may, of course, be dispensed with. I would also have it understood that when the latch is used on a sliding door or gate, a latch bar N² of the type shown in Fig. 8 will be substituted for the 15 bar N shown in Fig. 5.

In the practical operation of my improvements it will be readily understood that when the door is swung to its closed position, the latch bar will ride up to and seat 20 in the notch b of the keeper D in which position it will be retained by the action of the spring K; and it will also be apparent that when the door is swung open to the full extent the handle P will seat in the notch a 25 of the keeper C and will be retained therein by the action of the spring, with the result that the door will be securely held against casual closing. When however, it is desired to close the door, it is simply necessary 30 to turn the handle P, against the action of the spring, out of the notch a in keeper C, whereupon the door may be closed in the ordinary manner.

It will be obvious from the foregoing 35 that my novel latch may, with slight changes, be used to advantage for either a right or a left door.

In addition to the practical advantages hereinbefore ascribed to my novel latch, it 40 will be observed that the same is simple and inexpensive and may be applied with great facility to old as well as new doors and gates; also, that the latch is strong and durable and is, therefore, well adapted to 45 withstand the rough usage to which farm doors and gates are ordinarily subjected.

I have entered into a detailed description of the present and preferred embodiment of my invention in order to impart a full, 50 clear and exact understanding of the same, but it is obvious that in the future practice of the invention, changes in the form, construction and relative arrangement of parts may be made without involving departure 55 from the spirit of the invention as claimed.

Having described my invention, what I claim and desire to secure by Letters-Patent, is:

1. The combination of a door, a suitably 60 supported keeper, and a latch comprising a

tubular casing section extending transversely through the door, an end tubular casing section fixed with respect to the first-named section and arranged at one side of the door, an end tubular casing section 65 screwed on the first-named section and arranged at the opposite side of the door; one of said end tubular sections having a slot in its side, a spindle, of angular form in cross-section, extending lengthwise through 70 the casing sections and having a handle at the outer end of one end tubular casing section, a handle secured on the spindle and arranged at the outer end of the other end tubular casing section, a coiled spring surrounding the spindle and bearing at one end against the spindle and at its opposite end against the casing, and a latch bar extending through and movable in the said slot of the end tubular casing section and 75 having an angular aperture receiving the angular spindle.

2. The combination of a hinged door, a suitably supported keeper arranged adjacent the outer edge of the door, a suitably supported keeper arranged at the opposite side of the door, with reference to the first-named keeper, and a latch comprising a tubular casing section extending transversely through the door adjacent the outer edge thereof, an 80 end tubular casing section fixed with respect to the first-named section and arranged at one side of the door, an end tubular casing section 85 screwed on the first-named section and arranged at the opposite side of the door; one of said end tubular sections having a slot in its side, a spindle, of angular form in cross-section, extending lengthwise through 90 the casing sections and having a handle at the outer end of one end tubular casing section, a handle secured on the spindle and arranged at the outer end of the other end tubular casing section; one of said handles being open to engage the second-named keeper, a coiled spring surrounding the 95 spindle and bearing at one end against the spindle and at its opposite end against the casing, and a latch bar for engaging the first-named keeper, extending through and movable in the said slot of the end tubular 100 casing section and having an angular aperture receiving the angular spindle.

In testimony whereof I have hereunto set my hand in presence of two subscribing witnesses.

OLE T. BELSVIG.
